[57] ABSTRACT

A trailer supported cradle for boats which minimizes the force required to mobilize a boat with respect to its trailer during loading and unloading activities and which substantially increases the area of contact between the boat hull and its supporting cradle to reduce the stress on the hull of the boat due to acceleration forces developed during transportation of the boat upon the tractor-drawn trailer, said support including elongated endless belts trained about articulately mounted sets of coplanar pulleys.

BOAT CRADLE FOR MOBILE TRAILERS

BACKGROUND OF THE INVENTION

My present invention relates to boat trailers and more particularly to improved boat loading, supporting and unloading mechanism carried by transporting trailers.

When a boat is in the water, its hull is not normally subjected to localized areas of stress. However, since boating has become more popular, instead of one trip to a body of water at the beginning of the boating season and one return trip at the close thereof, it is now customary to transport a boat to and from its point of use each time it is used. A boat is thus subjected to unusual stresses at localized areas many times throughout the boating season. Heretofore, trailers have been provided with supporting rollers for supporting and cradling a boat hull during the loading and unloading operation and also during the movement of the boat from one location to another by means of a trailer. The rollers are normally constructed of at least a semi-rigid material and through they may be articulately supported upon the trailer, as in my prior U.S. Pat. No. 3,155,249, still they are normally fixed in-so-far as their contact with the hull of a loaded boat is concerned. The contact area between each roller and the outer surface of the hull of the boat comprises a thin line extending parallel to the axis of rotation of the roller and a length equal to the width of the roller. As the size and weight of boats increases the custom has been to multiply the number of rollers in an attempt to increase the supporting area and thereby minimize the localized hull stresses. However, as rollers are multiplied, the frictional resistance to loading and unloading movements increases proportionately.

As an alternative method of supporting the boat on a trailer during the trailing operation, pad assemblies having relatively large bearing surfaces were considered. This method was highly desirable during the trailing operations, inasmuch as the large load area of the pads distributed the portion of the weight of the boat supported by each pad over a large area. However, the method proved unsatisfactory because the boats did not readily slide onto and from the trailer when supported by the relatively large pad assemblies.

In view of the foregoing problems, there were attempts to provide a boat trailer which would support a boat during the trailing operations by means of pad assemblies having large bearing areas and by means of roller assemblies during the loading and unloading operations. While trailers of this type have been provided with some success, they have been complicated and have required considerable time and effort on the part of the boat owner, and, therefore have not been widely accepted. Most of the prior art assemblies which are provided with roller assemblies for loading and unloading the boat as well as pad assemblies for supporting a boat during a trailing operation have a tiltable frame section with roller support means thereon.

In U.S. Pat. No. 3,082,892, one such boat trailer having a tiltable frame section with roller support as well as pad assemblies is disclosed. When a tiltable section is tilted to the loading and unloading positions, the roller supports are elevated above the pad assemblies. Not only is it necessary to tilt the tiltable frame section in order to transfer the load of the boat from the pad as-

sembly to the roller support means and vice versa, but the hull is still subjected to the stress of being transferred to and from and moved over rollers. Thus the patent does not overcome the problem of relieving stress on the hull of the boat.

A trailer having a complicated, telescoping frame with a tiltable section is disclosed in U.S. Pat. No. 3,140,003. While the structure purports to reduce the manual labor, it does not solve the problems of stress and friction on the boat hull. Still another prior art trailer having a tiltable section is provided in U.S. Pat. No. 3,097,755. Once again, the hull of the boat is subjected to stresses and possible damage from the rollers. The above described trailers generally employ a conventional system of stationary rollers. The boat rides across the rollers during the loading and unloading and, consequently is subjected to a great deal of friction, stresses, bumping and the like.

SUMMARY OF THE INVENTION

The present invention includes elongated belts which are supported upon series of coplanar pulleys and thus provide the very substantial benefit of increased hull support area found in the pad assemblies of the prior art and yet obviate the necessity for increased rollers thus preventing any substantial increase in the forces required to move the boat with respect to the trailer.

Moreover, during the trailing operation, in addition to the load factors hereinbefore mentioned, there is an abrading function which takes place between the rollers and the boat hull with such severity, in some cases, as to wear through the varnish and gel coat. The dust and dirt stirred up by the movement of the vehicle and air results in abrasive granules being deposited upon the rollers and the continuous movements from trailing over the road results in its migration between the rollers and hull causing the spot wear. Over a period of time holes will develop at the support points.

The rapidity with which the movement and abrasive will wear the hull is, of course, varied by the P.S.I. supported at the rollers. My present invention reduces the forces involved from between 50 and 100 P.S.I. downwardly to from 3 to 5 P.S.I. preferably and thus materially reduces the abrading action during trailing operations.

Accordingly, it is an object of the present invention to provide an improved boat mobilizing and support mechanism for trailers.

Yet another object of the present invention lies in the provision of an improved boat mobilizing and support mechanism which distributes the load over an increased area of the hull and particularly does not localize any stress at the keel.

A further object of the present invention is to provide a unique endless belt admirably adapted to facilitate mobilization of the boat during loading and unloading operations, yet which provides ample hull support during transportation of the boat overland from place to place.

The foregoing and other objects and advantages of the present invention will become more apparent and meaningful during the course of the following specification when considered in association with the accompanying drawings wherein a preferred form of the invention is graphically illustrated. It is to be understood

however, that the drawings are illustrative only and are not intended to limit the scope of the invention. It should also be understood that various changes in construction may be resorted to in the course of manufacture without in any way departing from the spirit of the invention which is to be understood only in accordance with the appended claims. Furthermore, it is to be understood that while the invention is described in one particular association, it is not my intention to unnecessarily limit the applicability of the invention, but I desire to reverse to myself the claimed invention for every use of which it is now known or subsequently discovered to be susceptible.

Other advantages and features of this invention will become apparent from the more detailed description following in which like reference numerals are employed to designate similar parts in the accompanying drawings, wherein:

FIG. 1 is a perspective view of a boat trailer embodying the support mechanism constituting the subjects matter of this work;

FIG. 2 is an enlarged elevation of one supporting belt assembly;

FIG. 3 is a lateral section as at line 3—3 of FIG. 2;

FIG. 4 is a lateral section as at line 4—4 of FIG. 2 upon a further enlarged scale; and

FIG. 5 is a fragmentary perspective of a section of the novel belt.

DESCRIPTION OF PREFERRED EMBODIMENT

Referring now more particularly to the drawings, one embodiment of a boat trailer in accord with the present invention is shown generally at 10. The trailer includes a rigid frame, shown generally at 11, and having a longitudinally extending draft tongue 12 and mobilizing wheels 13, one journaled to support each side of the frame 11 in conventional manner. The forward end of the draft tongue may be provided with any suitable releasable coupling element as, for example, a conventional ball hitch socket (not shown) for engagement with a complementary element (not shown) adapted to be carried by a drawing vehicle or tractor.

Boat cradle means, shown generally by the numeral 14, are carried by the rigid frame 11 and constitute means for mobilizing a boat during loading and unloading movements and sequentially supporting the boat for transportation over land upon the trailer.

The boat cradle means 14 comprises plural, strategically disposed boat mobilizing and support means 15—15 of a predetermined selective quantity to provide plural supporting areas for the boat hull at points spaced from the boats keel (not shown) or the plate-roll median of the trailer frame 11.

Each support means includes an endless belt 16 having a boat support flight 16a presented so that its outer face 16b will contact the hull surface (not shown) of a boat. The belt 16 includes a truncated cuneate bead 17 midway the cross-flange 18 and on its inner face, opposed to the outer face 16b. Molded in the rubber-like body forming the bead 17 and flange 18 are spaced reinforcing leaves 19—19 united by non-extensible cables 20—20, which cables preclude unwanted stretching of the belt. The leaves 19—19 provide lateral edge support to the belt face 16b to maximize the load distribution of the hull face upon the support

flight face 16b. The said face 16b is laterally concave and thus the flight 16a has an elongate cylindroidal face which will yield to conform to the contour of a boat hull when sufficient gravitationally induced force is applied by the hull surface to the face 16b.

To facilitate mobilization of a boat onto and off from the cradle 14, the belts 15 are each trained to traverse a path dictated by coplanar pulleys 21 and 22 journaled on spindles 23—23 fixed to extend perpendicularly from the mounting bar 24 rockably carried by a finger 25 welded or otherwise secured in near spaced relation to a rock arm 26 fixed perpendicularly at the end of a frame mounted rock shaft 27. The rock shafts 27 are mounted for rocking movements on axes substantially parallel to the longitudinal axis of the trailer, whereby the rock arms 26 tilt in substantially vertical planes athwart of the axis of said trailer and the mounting bars pivot about the axes of the fingers 25; all said movements being within predetermined limits.

The pulleys 21 and 22 are provided with annular grooves companion to the beads 17 and thus provide means for precluding accidental displacement of the belts 15 from their paths.

25 The groove defining flanges 28—28 of the pulleys 21 and 22 are axially increased to provide annular support faces upon which the inner faces of the belt 16 are supported.

It is thus seen that I have provided plural spaced articulately supported boat mobilizing and support means which provides greatly increased hull support area over a similar quantity of rollers and yet one which provides very little, if any more resistance to movements of a boat during loading and unloading maneuvers.

35 Having thus described my invention, I desire to secure my Letters Patent of the United States the following:

1. In a boat trailer including a wheel-supported frame having a longitudinally extending draft tongue adapted to be releasably coupled to a tractor, means useable in loading, supporting and unloading a boat, said means comprising:

a boat cradle comprised of plural spaced boat mobilizing and support means supported at predetermined positions upon said frame and removed from a position corresponding to the keel of a boat;

40 at least selected ones of said boat mobilizing and support means each having plural co-planar pulleys journaled on substantially parallel axes disposed substantially athwart of the longitudinal axis of said trailer;

an endless belt trained about said pulleys to traverse an obround path peripherally of said pulleys and adapted to present a boat support flight to the hull of a boat supported upon said trailer;

45 said belt having a cylindroidal concave, axially co-planar outer face on said boat support flight and progressively more susceptible of pressure deformation from its center toward its opposed edges; and

50 means for precluding accidental displacement of said belt from its said path.

55 2. The combination of claim 1 wherein additionally, the said boat mobilizing and support means are articulately supported upon said frame for limited angulation

to substantially conform to the hull contour variations of a boat being moved longitudinally upon said trailer.

3. The combination of claim 2 wherein additionally pairs of said boat mobilizing and support means are pivotally mounted one at each end of a bar mounted to tilting movements in a vertical plane athwart of a trailer, there being means restricting all movements

within predetermined limits.

4. The combination of claim 3 wherein additionally fore and aft pairs of said boat mobilizing and support means are united for coincidental tilting movements in vertical planes athwart of the trailer.
